(57) **CLAIM**

The ornamental design for a terminal connector, as shown and described.

DESCRIPTION

FIG. 1 is a right side perspective view of the terminal connector;

FIG. 2 is a left side perspective view of the terminal connector illustrated in FIG. 1;

FIG. 3 is a rear end view of the terminal connector illustrated in FIG. 1;

FIG. 4 is a front end view of the terminal connector illustrated in FIG. 1; and

FIG. 5 is a left side view of the terminal connector illustrated in FIG. 1, the right side view being a mirror image thereof; and,

FIG. 6 is a top view of the terminal connector illustrated in FIG. 1, the bottom view being a mirror image thereof.

The portions of the device depicted in broken lines are for illustrative purposes only and form no part of the claimed design.

1 Claim, 4 Drawing Sheets
